FIG.1

FIG.2

FIG.3

FIG.4

FIG.5

FIG. 1 is a top plan view of a motorcycle seat showing my new design;

FIG. 2 is a side elevational view thereof;

FIG. 3 is a bottom plan view thereof;

FIG. 4 is a front elevational view thereof; and

FIG. 5 is a rear elevational view thereof.

The characteristic feature of my design resides in the specific pattern on the top of the seat and the front and rear of the backrest portion as best illustrated in FIGS. 1, 4 and 5.

I claim:

The ornamental design for a motorcycle seat, as shown and described.
